Primary Examiner — Sandra Snapp*Assistant Examiner* — Ieisha Price(74) *Attorney, Agent, or Firm* — Muncy, Geissler, Olds & Lowe, P.C.(57) **CLAIM**

We claim the ornamental design for a connector, as shown and described.

DESCRIPTION

FIG. 1 is a right, front, top perspective view of a connector showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a right, rear, top perspective view of the connector thereof;

FIG. 9 is a cross-sectional view of the connector, taken along line 9-9 in FIG. 6; and,

FIG. 10 is an environmental perspective view of the connector.

The broken lines in the drawings illustrate portions of the connector and depict environmental structure in FIG. 10. These broken lines form no part of the claimed design.
